UNITED STATES PATENT OFFICE.

WILLIAM C. SCHMIDT, OF RICHMOND, VIRGINIA.

INDICATING-BOTTLE.

1,228,832.

Specification of Letters Patent.

Patented June 5, 1917.

Application filed February 24, 1909, Serial No. 479,737. Renewed October 23, 1916. Serial No. 127,313.

To all whom it may concern:

Be it known that I, WILLIAM C. SCHMIDT, citizen of the United States, residing at Richmond, in the county of Henrico and State of Virginia, have invented certain new and useful Improvements in Indicating-Bottles; and I do hereby declare the following to be a full, clear, and exact description of the invention, such as will enable others skilled in the art to which it appertains to make and use the same.

My invention consists in certain new and useful improvements in indicating bottles. The object of my invention is to provide a closure for bottles intended to contain various kinds of liquids, so constructed as to permit the contents of a bottle to be freely poured therefrom but which will indicate with certainty any attempt to insert liquid into the bottle after it has once been emptied or partially emptied of its original contents.

To this end I provide my improved bottle with an indicating device having a part which is adapted to be totally or partially destroyed, disintegrated or removed by chemical action, which is set up by liquid coming in contact with a part impregnated with chemicals, thereby carrying with it a word or indication or symbol, showing the contents to be original and on dissolution, displaying a word or other indication showing the bottle to be refilled.

In order that the invention may be understood, I have illustrated it in the accompanying drawings, in which I have shown a form of bottle which I may employ, a closure for the same and also slight modifications thereof.

In the drawings, Figure 1 is a vertical sectional view of one form of my improved bottle and closure.

Fig. 2 is a similar view of a modification of my invention, with the stopper retracted.

Fig. 3 is a similar view of a further modification of my invention.

Fig. 4 is a top plan view of the closure or disk C on lines z—z of Fig. 2.

Fig. 5 is a top plan view of the member B on lines y—y of Fig. 2.

Fig. 6 is a similar view of the closure or disk C on lines x—x of Fig. 3.

Fig. 7 is a side view of the bottle neck when filled and closed ready for use.

Fig. 8 is a similar view showing the bottle open and that an attempt has been made to refill it.

Similar letters of reference indicate identical parts throughout.

A represents the neck portion of my improved bottle provided with my invention, and having internal screw threads *a* as shown. B is a member forming part of the closure for the bottle and consists of a screw threaded annular portion *b* adapted to engage the screw threads in the neck of the bottle.

F is a washer of cork or other suitable material seated in a recess in the neck of the bottle and below the threaded portion thereof, to prevent the contents of the bottle from passing the threads and entering the recess *c'*, by tightly screwing B against the washer F. At the top of the member B is a disk or flange C provided with serrations *c* at its outer edge. This disk is of such diameter in cross section as to leave a small space between its circumference and the inner surface of the neck of the bottle, and a deeper recess *c'* is provided between the disk or flange and the screw threaded portion of the member B so that a greater space is left between the inner surface of the neck of the bottle and the outer surface of the recessed portion of the member B, than between the circumference of the disk or flange C and the bottle neck, thus providing a cup like receptacle for the indicator. Around the disk or flange C, I place a band or ribbon E of some absorbent material such as blotting paper, substantially **E** shaped to form a baffle above and below the disk or flange C, as will hereafter appear, and in the recess *c'* I place a second piece or band of absorbent material similarly shaped as at E' in the drawings, and within the second baffle I place the indicator G.

K in Figs. 1 and 2 is a cylinder and is a part of member B, being connected with it by ribs which form channels *e*. The upper part of the cylinder K is threaded at *c*² to receive the shank *c*³ of the stopper D. The lower end of the cylinder K is closed by means of a stopper of suitable material, as a cork *k* to prevent the outflowing liquid from entering the said cylinder.

The indicator G consists of a ribbon or strip of any suitable material such as paper, fabric tape, etc., with an indication of fraud thereon, such as the word "refilled," coated with a mixture of non-transparent substances, and chemicals as whiting mixed with a non-hygroscopic substance, as a car-

bonate and preferably bicarbonate of soda which conceals the fraud indication.

On this coating appears by printing, stamping or otherwise any desired word or 5 words, marks or symbols indicating originality of the contents, such for example as the word "Original" which indications are visible through the bottle as shown in Fig. 7.

At the back of this ribbon or strip is 10 placed another ribbon or strip of absorbent material, which is impregnated with a non-hygroscopic solid acid, such for example as citric acid, which is easily soluble in liquid. The acid may be placed in close proximity 15 to the indicator without the use of a strip of absorbent material.

When an attempt is made to refill the bottle, the inflowing liquid will be forced into contact with the two ribbons and a chemical 20 and mechanical action ensues which destroys the coating on which the indication of originality appears and the said coating is chemically removed carrying with it the indication of originality and displaying the 25 indication of fraud. The removal of the indication of originality and coating is mechanically accelerated by the carbonic acid gas formed by the action of the chemicals used.

30 It is obvious that instead of having two separate ribbons or strips, a single ribbon or strip may be used, one side being coated with a non-hygroscopic carbonate and the other side impregnated with a suitable acid.

35 It is also perfectly obvious that fraud indications, such as the word "Refilled" may be coated as heretofore described, and no further indication printed on the coating, the plain coating being the evidence of 40 originality. In this case the attempt to refill the bottle would destroy the coating as heretofore described, and disclose the fraud indication, or the plain ribbon might be the indication of fraud, coated as described, 45 with the symbol of originality thereon. In this case an attempt to refill the bottle would destroy the coating and the symbol of originality leaving the plain ribbon to indicate fraud. Many variations of my improved 50 indicating ribbon may occur in the practical application of my invention.

In Figs. 1 and 2 the member B is so formed that by means of ribs, passages e are provided for the outlet of liquid from the 55 bottle.

The stopper D may be of any desired form, the one shown consisting of a main portion D' provided with the screw threaded shank c² which engages the screw threaded opening c² of the part C in Fig. 3 or the upper part of K in Figs. 1 and 2. The stopper is provided with cored washers which close the mouth of the bottle and channels by screwing the stopper shank c³ into the 60 65 opening c².

A ring d is provided for the shank after it is in place to prevent the entire withdrawal of the stopper but allowing the same to be unscrewed a sufficient distance to open the mouth of the bottle and passages e for the purpose of decanting the contents 70 of the bottle.

In Fig. 1, the parts B and C are made integral and the stopper shank is inserted through the opening c² and keyed in place 75 by means of the ring d.

The indicating device as described, is then placed in position and also the baffles of absorbent material, as shown and the part B then screwed into the neck of the bottle and permanently secured by means of cement against the washer F. The bottle is 80 then ready for the market.

In decanting the contents, in case of any backward drip when a portion only of the 85 contents is poured out, such dripping is caught by a plurality of protecting baffles and the indicating ribbon is thus protected, but when an effort is made to refill the bottle, the incoming liquid will pass the baffles and will come in contact with the indicating ribbon or ribbons setting up the chemical and mechanical action heretofore described, and it will become apparent to 90 the user that the bottle has been refilled. 95

The construction shown in Fig. 2 is the same as that shown in Fig. 1, except that the parts B and C are made separate, the disk C being permanently screwed to the part B as at H. The lower portion of the 100 part B is also provided with an annular partition I of some transparent substance, such as glass or other suitable material, forming two chambers, one for each of the two ribbons heretofore described. This partition is in effect a baffle and acts in the place of the lower baffle already described. 105

The indicating ribbon coated with the non-hygroscopic carbonate, is placed in the outer chamber and the ribbon impregnated with 110 the acid is placed in the inner chamber, thereby preventing any chemical action until enough liquid is forced into the outer chamber to overflow the partition I when the chemical action heretofore described will 115 be set up.

Fig. 3 is identical with Fig. 2 except that the cylindrical portion K of the part B is omitted, the threads being formed in the ribs L of the disk, Fig. 6, to engage the stem c³ of the stopper D'. In this view the indicating ribbon is shown as a single ribbon or two ribbons back to back, the outer surface or ribbon bearing the fraud indication and coating of non-hygroscopic substance, and the inner surface or ribbon being impregnated with acid. In this view I have also shown a conical valve X which is loosely placed in the narrowed portion of the neck of the bottle. This valve when the bottle 120 125 130

is inverted will permit the ready outflow of the contents of the bottle, but will act as an additional deterrent to refilling the bottle, and in case an attempt is made to force liquid into the bottle the valve will close the bottle and cause the liquid to fill the recess in which the indicator is located.

5 This indicating ribbon or double ribbon is placed in the inner chamber. It is obvious that the partition I will protect the ribbon from backward drippings and no absorbent baffles will be necessary, but that in an attempt to refill the bottle, the outer chamber will quickly overflow the partition I, and the liquid entering the inner chamber will cause the chemical and mechanical action heretofore described, to take place and show the bottle to be refilled.

10 One form of ribbon which I have contemplated using consists in a strip of suitable material impregnated with citric acid and having characters of originality thereon formed preferably of bi-carbonate of soda. These characters are chemically removed by 15 the citric acid in solution with the inflowing liquid.

What I claim and desire to secure by Letters Patent is:—

1. An indicating bottle of the kind described having in the neck thereof an indicating device visible from the exterior of the bottle, said indicator comprising a plurality of chemicals and a fraud indicating character, the character being invisible when 35 the contents of the bottle are original, and the chemicals being adapted when in solution caused by inflowing liquid, to form a chemical solution which is adapted to bring said indicating character to view.

2. An indicating bottle of the kind described, having in the neck thereof an indicating device visible from the exterior of the bottle, said indicator comprising a plurality of chemicals and a fraud indicating character, a coating covering said indicating character and rendering it invisible from the exterior of the bottle, and the chemicals being adapted when in solution caused by inflowing liquid to form a chemical combination, which is adapted to destroy said coating to display said fraud indicating character.

3. An indicating bottle of the kind described, having in the neck thereof an indicator visible from the exterior of the bottle, said indicator comprising a plurality of chemicals and a fraud indicating character, the character being invisible when the contents of the bottle are original, and one of 55 said chemicals being adapted to react chemically upon another when in solution caused by inflowing liquid, whereby said fraud indicating character is exhibited to the vision.

4. An indicating bottle of the kind described, having in the neck thereof an indi-

cator visible from outside the bottle, said indicator comprising a non-hygrosopic carbonate coating, and an absorbent material impregnated with a non-hygrosopic acid the acid being easily soluble in liquid.

5. An indicating bottle of the kind described having in the neck thereof an indicator visible from outside the bottle, said indicator comprising a coating of bicarbonate of soda, and an absorbent material impregnated with citric acid, whereby when liquid is brought into contact therewith, the coating is removed carrying therewith an indication appearing thereon and displaying an indication covered thereby.

6. An indicating bottle of the kind described having in the neck thereof an indicator visible from outside the bottle, said indicator coated with a non-hygrosopic carbonate and a non-hygrosopic soluble acid in close proximity thereto.

7. An indicating bottle of the kind described having in the neck thereof an indicator visible from outside the bottle, said indicator comprising a ribbon of suitable material, one side of said ribbon bearing an indication and provided with a carbonate coating concealing said indication and the other side of said ribbon being impregnated with an acid easily soluble in liquid.

8. An indicating bottle of the kind described having in the neck thereof an indicator visible from outside the bottle, said indicator comprising a strip of absorbent material, one side of said strip bearing an indication and being provided with a non-transparent carbonate coating concealing said indication, said coating also bearing an indication thereon, and the other side of said strip being impregnated with an acid easily soluble in liquid.

9. An indicating bottle of the kind described, having a member in the neck thereof provided with an exterior recess forming with the neck of the bottle a chamber, an indicating device provided in said chamber and visible from the exterior of the bottle, said indicator comprising a plurality of chemicals and a fraud indicating character which is invisible when the contents of the bottle are original, and one of said chemicals being adapted to react chemically upon another when in solution caused by inflowing liquid, for the purpose of exhibiting the fraud indicating character, and baffles provided in said chamber to protect the indicator from the return drippings of the outflowing liquid but permitting the operation of the indicator when there is an excessive inflow of liquid.

10. An indicating bottle of the kind described, having a member in the neck thereof provided with an exterior recess forming with the neck of the bottle a chamber, an indicating device provided in said chamber

and visible from the exterior of the bottle, absorbent baffles provided in said chamber to protect the indicator from the return drippings of the outflowing liquid, but permitting the operation of the indicator when there is an excessive inflow of liquid.

11. An indicating bottle of the kind described having a member in the neck thereof provided with an exterior recess forming with the neck of the bottle a chamber, an indicating device provided in said chamber and visible from the exterior of the bottle, said indicator comprising a plurality of chemicals and a fraud indicating character which is invisible when the contents of the bottle are original, one of said chemicals being adapted to react chemically upon another when in solution caused by inflowing liquid, for the purpose of exhibiting the fraud indicating character, said member being also provided with channels through the center of the same, through which the contents of the bottle may be discharged, and means for causing inflowing liquid to enter the chamber from above.

12. An indicating bottle of the kind described having a member in the neck thereof provided with an exterior recess forming with the neck of the bottle a chamber for an indicating device said device being visible from outside the bottle, a central portion having a threaded opening for engaging the threaded stem of a stopper and a discharge passage for the contents of said bot-

tle between said central portion and the outer walls of the said member, means for preventing liquid from entering the chamber from below and means for admitting inflowing liquid from above into said chamber.

13. An indicating bottle of the kind described having in the neck thereof, an indicator visible from outside the bottle comprising a strip of suitable material impregnated with an acid easily soluble in liquid and characters formed of bi-carbonate of soda provided on one side of said strip.

14. An indicating bottle of the kind described, having in the neck thereof, an indicator visible from the exterior of the bottle, said indicator comprising a base containing a plurality of chemicals and a plurality of fraud indicating means, one of said indicating means being visible and the other invisible when the contents of the bottle are original, and one of said chemicals being adapted to react chemically upon another when in solution caused by inflowing liquid, whereby the visible indicating means is destroyed and the invisible indicating means brought into view.

In testimony whereof I affix my signature, in the presence of two witnesses.

WILLIAM C. SCHMIDT.
